BOX CLOSING TOOL

Alfred L. Rosenmund, Rockaway, N. J., assignor
to Stapling Machines Co., a corporation of
Delaware

Application March 16, 1938, Serial No. 196,161

10 Claims. (Cl. 140—123)

This invention relates to a tool for closing wirebound boxes.

It is an object of the invention to provide a tool which will efficiently and rapidly effect a closure of loop ends of box-binding wires.

It is a further object of the invention to provide a tool which will not unduly strain the wire during a closing operation.

It is a further object of the invention to provide a tool which will effect an efficient closure without damaging either the contents or the container.

It is a further object of the invention to provide a tool of the character described which will automatically draw or force the lid or cover of the box into closed position.

In the drawings:

Figure 1 is a side elevation of the illustrative tool, with the parts in normal position to start a box closing operation.

Fig. 2 is a side elevation partially sectioned, showing the position of the parts after the box lid or cover has been forced down to closed position and the U-shaped fastener on the lid or cover has been bent down against the front side of the box.

Fig. 3 is a side elevation viewed from the left in Fig. 1.

Fig. 4 is an enlarged sectional view of the means for releasably holding the parts in the normal position shown in Fig. 1.

Fig. 5 is a perspective view of a wirebound box showing the top section partially closed and in position to be operated upon by the tool of this invention.

Fig. 6 is an enlarged side elevation of a corner of the box of Fig. 5, showing the tool at the start of a closing operation.

Fig. 7 is a similar side elevation after the tool has contacted the top fastener, forced the top section down, and bent the top fastener down toward the face of the front section of the box.

Fig. 8 is a similar side elevation after the tool has been swung down to bend the front-section fastener over the top-section fastener to effect a hooking engagement between the two fasteners and secure the top section in closed position.

Fig. 9 is a side elevation of the corner of the box showing how the closure may be pressed toward the box by the steel ferrule on the handle of the tool.

Fig. 10 is a perspective view of the box corner showing the finished closure.

As conducive to a better understanding of this invention, it should be noted that in wirebound

boxes of the type shown in Fig. 5 the lid or cover section is hingedly connected to the rear section by the binding wires and may be raised or lowered like the lid of a trunk. The lid or cover section is secured in closed position by hooking 5 the wire loop fasteners on the front section through the wire loop fasteners on the cover section as shown in Fig. 10.

When the box is used for the shipment of commodities such as fruits or vegetables, which 10 have a tendency to settle during storage or transit, it is the practice to overload the box initially so that when the commodity settles, the box will still be substantially full. Great difficulty has been encountered in closing the lid of such an 15 overloaded box prior to hooking the loop fasteners together. In some instances a power press has been used. In other instances the operator has been obliged to press the lid down by hand or with his knee and hold it down while hooking 20 the loop fasteners together.

The tool of this invention is intended to perform the hooking operation and at the same time force down the lid of the box, thus reducing the time and labor required to close the box and 25 contributing to a uniformly tight closure.

Referring to Fig. 1, a head 1 supports the several elements of the tool. Extending downwardly from the head 1 is a round shank 2 terminating in a flat reduced portion 3 provided 30 with a hook 4. Mounted to slide vertically in a lateral recess 5 in shank 2 is a rod 6, on the lower extremity of which is formed a notch 7 shaped substantially like an inverted U. The upper end of rod 6 is fixed to a collar 8 which 35 surrounds shank 2 and is slidable thereon.

Collar 8 and rod 6 are moved up and down on shank 2 by a lever arm 11 having an angled flat portion 12 pivoted to head 1 at 13 and pivotally connected at its extremity 15 to a link 40 14, the other end of which is pivoted at 17 to an ear 16 on collar 8. As shown more clearly in Fig. 3, lever arm 11 is provided with a handle 18, preferably of wood, held in position on lever arm 11 by a steel ferrule 19. This portion of lever 45 arm 11, carrying the handle 18 and steel ferrule 19, is bent to project to the right of and at a right angle to lever arm 11.

Referring to Figs. 1, 3, and 4, and particularly to Fig. 4, there is shown an automatic 50 locking device for holding the parts in the position shown in Fig. 1, i. e., with the rod 6 in the raised position there shown.

The locking device comprises a pin 20 having a rounded head 21 reciprocally mounted in a bore 55

23 in head 1. A spring 24 housed in bore 23 between head 21 and a shoulder 25 holds pin 20 normally in an extended position with its rounded head 21 protruding beyond the surface of head 1 of the tool. Pin 20 and its rounded head 21 may be adjusted in the bore 23 by a nut 26 threaded on pin 20.

Upon the up stroke of collar 8, pin 20 enters a recess 30 in a latch 27 secured to collar 8 by screws 28. The upper extremity of latch 27 is provided with a beveled surface 29 to contact head 21 and force it into the bore 23 until the recess 30 is opposite head 21, at which time the spring 24 will force head 21 into recess 30 and hold collar 8 and rod 6 in raised position until lever arm 11 is operated to release the locking device.

The tool is operated in the following manner:

In Fig. 5 is shown a box 31 bound with wires 32 provided with fasteners 33 and 35 on their respective ends. Fastener 33 on top section 34 is wider than fastener 35 on front section 36, as shown in Fig. 10, so that fastener 33 may be readily placed over fastener 35.

In Fig. 5 the top section 34 is in position for closing by the tool of this invention. In this position, the fastener 35 on the front section extends up to or through the fastener 33 on the top section.

Referring to Fig. 6, hook 4 of shank 2 is hooked under fastener 35 of front section 36. The handle end of lever arm 11 is then moved upwardly to the position shown in Fig. 7. This movement of arm 11, acting through link 14, forces collar 8 and rod 6 downward. Downward movement of rod 6 causes notch 7 at the lower end of rod 6 to engage fastener 33 of top section 34 and force top section 34 down into contact with side section 36 and at the same time bend fastener 33 down tightly over the edge of top section 34, as shown in Fig. 7. From this position the tool is swung outwardly from the box and downwardly to the position shown in Fig. 8, thus hooking fastener 35 around the bight of fastener 33 with enough tension to hold top section 34 in closed position and to secure interengagement of fasteners 33 and 35.

The tool is readily disengaged by raising handle 18 slightly upward toward the closure so that hook 4 disengages fastener 35. Fasteners 33 and 35 may be positioned against the face of front section 36 by using the steel ferrule 19 as a hammer, as shown in Fig. 9, or by simply pushing the fasteners toward the face of the front section with a thumb or finger.

The term "loop-fastener" as used in the claims is intended to include the U-shaped type of fastener shown at 33 and 35 of the drawings.

I claim:

1. A tool for closing the lid of a wirebound box

having loop fasteners on the front and lid sections respectively, comprising a hooked member to engage one loop fastener, a notched member to engage the other loop fastener, and means to cause relative movement between said members to draw one loop fastener through the other loop fastener. 5

2. A tool according to claim 1, in which means are provided for releasably locking said members against relative movement.

3. A tool for closing a box having loop fasteners 10 on adjacent sections, comprising a pair of relatively movable members each adapted to engage a loop fastener, and means to cause relative movement therebetween to draw one loop fastener through the other loop fastener. 15

4. A tool according to claim 3, in which means are provided for releasably locking the members against relative movement.

5. A tool according to claim 3, in which one of the relatively movable members is slidably 20 mounted on the other member.

6. A tool for closing the lid of a wirebound box having loop fasteners on the front and lid sections respectively, comprising a member to engage and hold the loop fastener on the front 2 section and a member to engage and move the loop fastener on the lid section over the loop fastener on the front section.

7. A tool for closing the lid of a wirebound box having loop fasteners on the front and lid sections respectively, comprising a member to engage and hold the loop fastener on the front section and a member to engage and move the loop fastener on the lid section over the loop fastener on the front section and down toward the 3 face of the front section.

8. A tool for closing the lid of a wirebound box having loop fasteners on the front and lid sections respectively, comprising a member to engage and hold the loop fastener on the front section and a member to engage and move the loop fastener on the lid section and over the loop fastener on the front section and tension said loop over the edge of the top section.

9. A tool for closing a box having loop fasteners on adjacent sections, comprising a member to engage and hold one loop fastener and a member to engage and move the other loop fastener over the first loop fastener to interengage the two fasteners.

10. A tool for closing a box having loop fasteners on adjacent sections, comprising a pair of members relatively movable in parallel planes and each adapted to engage a loop fastener, and means to cause relative movement between said members to draw one loop fastener through the other loop fastener.

ALFRED L. ROSEN MUND.
